UNITED STATES PATENT OFFICE

WILHELM KAISER, OF BERLIN-SCHMARGENDORF, GERMANY, ASSIGNOR TO DEUTSCHE GASGLUHLICHT-AUER-GESELLSCHAFT M. B. H., OF BERLIN, GERMANY, A CORPORATION OF GERMANY

LIFE RESTORING APPARATUS

Application filed January 17, 1931, Serial No. 509,348, and in Germany January 23, 1930.

The methods of resuscitation practised up to the present, that is to say producing an artificial vacuum and superpressure in the lungs by means of compressed oxygen, breathing by the motion of the arms and compression of the thorax (either mechanically or by hand) or by inducing and compressing the abdominal integument of the patient by means of the so-called abdominal bell, show the following drawbacks. In connection with the two methods mentioned first the head and the upper extremities of the patient are not accessible to injections or other medical treatment. If the latter is necessary, for instance pulling out the tongue of the patient, the treatment of resuscitation must always be interrupted. Generally in a like manner the treatment of resuscitation must also be stopped during vomiting. The influence upon the circulation of the blood is very slight in connection with the method of causing artificial breathing by manipulating the function of the thorax by hand. Breathing by means of the abdominal bell is technically complicated and its application is expensive.

These inconveniences are overcome by the present invention. The subject matter of the invention refers to an arrangement in which the abdominal parts of a patient resting on his back, by raising of the nates and pressing the upper parts of his thighs upon the abdomen, are caused to be pressed against the diaphragm thus reducing the volume of the lungs (exhalation). During the contrary movement there occurs a relaxation of the lungs and an increase of the volume (inhalation). By causing alternatively a superpressure and vacuum in the abdominal cavity a circulation of the blood from and into said abdominal cavity is obtained. This method of breathing will be assisted by changing the position of the person to be resuscitated, namely by changing the position of the patient from the horizontal to the inclined head position. This change of position can be effected simultaneously with the movement of the legs. But it is also possible to carry on both movements separately, so that during vomiting of the person to be re-

suscitated the breathing function by means of the legs can be effected during the fixed inclined position. It is also possible, to fix the position horizontally in case there should occur a disturbing rush of blood to the upper parts of the body of the patient.

An embodiment of the arrangement according to the present invention is illustrated in the drawing by way of example.

Figure 1 is a side elevation of the apparatus.

Figure 2 is a similar view showing the patient in a different position.

Figure 3 is another view, in which the patient, rests in still another position, and Fig. 4 is an end elevation of the apparatus.

Referring to the drawing, the apparatus consists of a board or couch *a* fixed horizontally by the arresting devices *b* and *b*¹. At a suitable point on this couch are provided two levers *c*, which if desired may be connected to one another at their free ends. The said levers are adapted to turn about an axis *d*. The legs of the person to be resuscitated are attached to the levers by means of the carrying devices *e*, consisting of rigid or movable straps, transverse bars or the like, secured to said levers. The couch may be fulcrumed at *f* about an axis vertical to the direction of the body. The couch is required to execute a turning movement to one side only, namely to that where the head of the patient is resting and in such a manner, that the upper portion of the patient's body is inclined toward the bottom. When inclining the couch the body of the person secured thereto in fixed position is retained thereon for instance by means of supporting means *g* adapted to be adjusted in accordance with the size of the person resting on said couch and which in the illustrated example passes around the patient's neck.

When the couch is in horizontal position the person to be resuscitated is secured within the levers in such a manner that the upper parts of the thighs form an angle of more than 90 degrees to his upper body. By moving the levers the upper parts of the thighs are pressed against the abdomen. At the same time the person to be resuscitated is

brought from the horizontal into the inclined head position (exhalation). By returning the levers in opposite direction until they reach their initial position, the horizontal position of the patient is obtained again (inhalation). Suitable spring elements h and h' serve to reduce the striking force or impact of the couch with the floor. If it is necessary to fix the couch in an inclined position, for instance, when the patient is vomiting, this inclined position can be attained by turning the couch a about the axis f . The breathing function with the aid of the legs may then be continued independently. In the same manner an independent horizontal position is possible. The advantages of the apparatus consist in a thorough exchange of air by means of a strong diaphragm breathing, in a strong action upon the circulation of the blood owing to the compression of the abdominal parts, in the possible inclined position of the upper extremities (filling of the head with blood), in rendering accessible the head without interrupting the operation of resuscitation (pulling out the tongue of the patient and so on), in rendering accessible the arms for the purpose of injection and for observing the pulse, as well as in the possibility of preventing by an inclined position of the patient the vomited substances from entering the bronchial ways, without the necessity of interrupting the operation of resuscitation. By forming the said couch a into a stretcher, a handy and effective apparatus is obtained.

I claim:

1. Apparatus adapted for resuscitation by diaphragm breathing comprising in combination a couch dimensioned to support the patient completely in a reclining position, two levers pivotally secured to said couch, and attaching means provided on said levers adapted for attachment to the legs at the knees of the patient whereby a pivotal manipulation of said levers will force the thighs of said patient into pressing engagement with the abdomen of the patient and out of contact therewith to stimulate abdominal breathing.

2. Apparatus adapted for resuscitation of the character described comprising in combination a couch dimensioned to support the patient completely in a reclining position, two levers pivotally secured to said couch, a support carrying an axis perpendicular to the direction of the body of the patient, about which axis the couch may be swung to adjust and sustain said patient in different reclining positions and attaching means provided on said levers adapted for attachment to the legs at the knees of the patient whereby a pivotal manipulation of said levers will force the thighs of said patient into pressing engagement with the abdomen of the patient and out of contact therewith to stimulate

abdominal breathing in any position of said couch.

3. Apparatus adapted for resuscitation of the character described comprising in combination a couch dimensioned to support the patient completely in a reclining position, two levers pivotally secured to said couch, a support carrying an axis about which the said couch and the patient thereon may be swung into an inclined head position, means for preventing a swinging of said couch to an inclined legs position and attaching means provided on said levers adapted for attachment to the legs at the knees of the patient whereby a pivotal manipulation of said levers will force the thighs of said patient into pressing engagement with the abdomen of the patient and out of contact therewith to stimulate abdominal breathing in any position of said couch.

4. Apparatus adapted for resuscitation of the character described comprising in combination a couch dimensioned to support the patient completely in a reclining position, two levers pivotally secured to said couch, a support carrying an axis about which the said couch and the patient thereon may be swung into an inclined head position and into a horizontal position and attaching means provided on said levers adapted for attachment to the legs at the knees of the patient whereby a pivotal manipulation of said levers will force the thighs of said patient into pressing engagement with the abdomen of the patient and out of contact therewith to stimulate abdominal breathing in any position of said couch.

5. Apparatus adapted for resuscitation of the character described comprising in combination a couch dimensioned to support the patient completely in a reclining position, two levers pivotally secured to said couch, a support carrying an axis about which the said couch and the patient thereon may be swung to different positions, and rigid attaching means provided on said levers adapted for attachment to the legs of the person to be resuscitated whereby pivotal operation of the levers will develop an unrestricted bending of the knees of the patient to press the thighs of said patient into engagement with the abdomen and out of contact therewith to stimulate abdominal breathing.

6. Apparatus adapted for resuscitation of the character described comprising in combination a couch dimensioned to support the patient completely in a reclining position, two levers pivotally secured to said couch, a support carrying an axis about which said couch and the patient thereon may be swung to different positions, and movable attaching means provided on said levers adapted for attachment to the legs of the person to be resuscitated, whereby pivotal operation of the levers will develop an unrestricted bend

ing of the knees of the patient to press the thighs of said patient into engagement with the abdomen and out of contact therewith to stimulate abdominal breathing.

6 7. Apparatus adapted for resuscitation of the character described comprising in combination a couch dimensioned to support the patient completely in a reclining position, two levers pivotally secured to said couch, a 10 support carrying an axis about which said couch and the patient thereon may be swung to different positions, attaching means for securing the legs of the patient to the levers whereby pivotal operation of said levers will 15 press the thighs of the patient into engagement with the abdomen and out of contact therewith to stimulate abdominal breathing, and means adjustable to the size of the patient, for fixing the latter against movement 20 on the couch.

8. Apparatus adapted for resuscitation of the character described comprising in combination a couch dimensioned to support the patient completely in a reclining position, 25 two levers pivotally secured to said couch, a support carrying an axis about which said couch and the patient thereon may be swung to different positions, attaching means for securing the legs of the patient to the levers 30 whereby pivotal operation of said levers will press the thighs of the patient into engagement with the abdomen and out of contact therewith to stimulate abdominal breathing, and means co-operating with the opposite end 35 of the said couch to permit the latter to be adjusted from a horizontal into an inclined position and vice versa.

9. Apparatus adapted for resuscitation of the character described comprising in combination a couch dimensioned to support the patient completely in a reclining position, two levers pivotally secured to said couch, a support carrying an axis about which said couch and the patient thereon may be swung 45 to different positions, attaching means for securing the legs of the patient to the levers whereby pivotal operation of said levers will press the thighs of the patient into engagement with the abdomen and out of contact therewith to stimulate abdominal breathing, and means located at opposite ends of the 50 said couch co-operating with each other to fix the latter in a horizontal position, one of said means functioning separately to fix said couch in an inclined position.

10. Apparatus adapted for resuscitation of the character described comprising in combination a couch dimensioned to support the patient completely in a reclining position, two levers pivotally secured to said couch, a support carrying an axis about which said couch and the patient thereon may be swung to different positions, attaching means for securing the legs of the patient to the levers 60 whereby pivotal operation of said levers will

press the thighs of the patient into engagement with the abdomen and out of contact therewith to stimulate abdominal breathing and buffer means secured to the said couch and adapted to absorb shocks resulting from impact of the latter with the floor.

In testimony whereof I affix my signature.
